UNITED STATES PATENT OFFICE

1,931,281

FURNACE STOKER

Joseph S. Bennett, Philadelphia, Pa., assignor to
 American Engineering Company, Philadelphia,
 Pa., a corporation of Pennsylvania

Application September 25, 1931
 Serial No. 565,160

6 Claims. (Cl. 122—376)

This invention relates to improvements in furnace stokers, and the invention in principle has an application of particular value to the overfeed sections of underfeed stokers of the general type disclosed in the pending U. S. application of Herbert E. Preston, Serial Number 263,900.

One object of the invention is to provide a stoker incorporating novel means for cooling the fuel-supporting elements.

10 Another and more specific object of the invention is to provide a novel design of stoker parts permitting regulated cooling of the parts by means of a liquid-cooling medium.

Still another object of the invention is to provide in a stoker of the multiple retort underfeed type, a novel design of overfeed section wherein provision is made for cooling said section by means of a liquid-cooling medium.

20 A still further object of the invention is to provide a novel and improved form of extension grate having provision for circulating a fluid medium in conductive relation with the fuel-supporting elements of the grate.

Another object is to provide a novel and improved form of fluid-cooled lower grate structure.

25 Still another object is to provide in conjunction with stoker parts as set forth above, a system of low-grade fluid-cooling whereby the temperatures of said parts may be maintained below the burning or fusion point without extracting appreciable amounts of heat from the furnace.

The invention further resides in certain novel and improved structural features and mechanical details hereinafter set forth and illustrated in the attached drawing, in which:

Figure 1 is a more or less diagrammatic vertical sectional view of the lower or overfeed section of a multiple retort underfeed stoker wherein said parts are constructed in accordance with the present invention, and

Fig. 2 is a section on the line 2—2, Fig. 1.

With reference to the drawing, the reference numeral 1 designates generally the lower or overfeed section of a multiple retort underfeed stoker of the general type disclosed in U. S. Patent No. 1,443,202, this portion of the stoker being mounted in the present instance upon an underlying supporting structure 2. The overfeed section comprises the dead plate 3 in which the retorts and tuyères (not shown) terminate and onto which the fuel is emptied from the said retorts by action of the fuel-feeding elements. Mounted below the dead plate 3 is an extension grate 4 which in the present instance

is adapted for forward and backward reciprocation between the dead plate 3 and the lower grate 5, which latter constitutes the forward wall of the stoker ash pit. In the bottom of this pit is mounted in the present instance a pair 60 of crusher rolls 6, and the said forward wall of the ash pit is illustrated as comprising at the lower portion and adjacent one of the crusher rolls 6 a crusher plate 7 whose function is well understood in the art and which constitutes no part of the present invention. 65

In the present instance, the extension grate 4 is composed of a plurality of transverse sections, a cross sectional view of one of which is shown in Fig. 2, and these sections are reciprocated by means in the present instance of rods 8 attached to the respective grate sections and connected to suitable actuating mechanism (not shown). 70

In accordance with my invention, the extension 75 grate sections are formed in the upper or fuel-supporting section with a series of channels 9 which in the present instance extend from the upper forward edge of the grate to the lower rear edge; and intermediate these channels are 80 formed series of passages 11 which extend from the lower to the upper surface of the grate and which constitute means for passing combustion air through the grate to the fuel-bed. Into the upper end of each of the channels 9 extends a 85 pipe 12, these pipes being connected in the present instance to the hollow interior of the dead plate 3, the dead plate in effect constituting a reservoir from which water is fed to the extension grate. Those portions of the pipe 12 90 which enter the channels 9 extend parallel to the direction of movement of the extension grate sections and are of sufficient length to afford the extension grate sections a normal movement while maintaining intact the fluid connection between the pipe and the said channels 9. 95

Extending forwardly from the lower end of each of the channels 9 and under the grate 4 is a pipe 13 which at its extremity extends downwardly and again towards the rear of the furnace and into the interior of the lower grate 5 at the upper end of the latter. The pipe 13 is of sufficient length to afford a maximum movement of the extension grate in its normal reciprocation while maintaining the fluid connection between the pipe and the interior of the lower grate 5. 100

The lower grate 5 is shown as composed of a series of blocks 14 superimposed one upon the other and suitably supported in the relatively 105

110

fixed structure of the lower portion of the stoker. In general construction, this lower grate may conform to that disclosed in the aforesaid U. S. application, Serial Number 263,900, although it 5 may vary widely as to structural details. Each of the blocks 14 is shown as having at its inner surface an inclined surface 15, and these surfaces on adjacent blocks are inclined to the vertical in reverse directions and are so relatively 10 located that the lower end of one overlies a portion of the immediately underlying surface. The arrangement is such that water discharged from the pipe 13 and directed against the surfaces 15 of the upper series of blocks through the medium of a baffle 16 will be directed over the faces of each of the inclined surfaces 15 of the entire series of underlying blocks, this water eventually being deposited in the bottom of the ash pit above the crusher plate 7.

20 In practice, a supply of water from a suitable source is maintained within the dead plate 3, from which it flows through the pipe 12 into the channels 9 of the extension grate, downwardly through the latter and through the pipe 25 13 onto the baffle 16. From the baffle 16, the water flows in a substantially continuous sheet over the surfaces of the elements 15 of the facing members of the lower grate 5. By this circulation of water, a highly efficient cooling of the 30 dead plate 3, the extension grate and the lower grate 5 is effected. These elements, constituting the overfeed section of the stoker, are subject to extremely high temperatures by reason of direct contact with the incandescent fuel. In accordance with my invention, maintenance of 35 these elements is materially aided by provision of cooling means so regulated as to maintain the elements at temperatures below the point of burning or fusion while at the same time not 40 withdrawing any appreciable heat from the furnace. The degree or amount of cooling may be varied as required by simple regulation of the water supply to the dead plate 3.

It will be apparent that the invention in principle 45 is applicable to other than the overfeed sections of mechanical underfeed stokers, and that as regards the specific embodiment of the invention shown for the purpose of illustration, the structural details may vary widely without 50 departure from the invention. While, for example, the water in the illustrated embodiment flows through the dead plate 3 to the extension grate, and thence to the lower grate, it is apparent that each of these elements may have a 55 separate source of supply.

I claim:

1. In the overfeed section of a mechanical underfeed stoker, the combination with a hollow dead plate constituting a reservoir for a liquid-cooling medium, of an extension grate movably mounted below said dead plate, means for actuating said extension grate, and means for directing a liquid from said dead plate into said extension grate to thereby effect a cooling of the latter. 85

2. In the overfeed section of a mechanical underfeed stoker, the combination with a hollow dead plate constituting a reservoir for a liquid-cooling medium, an extension grate mounted below said dead plate, said extension grate being formed with a plurality of channels in the fuel-supporting portion thereof, and means for conducting liquid from said dead plate into the upper ends of said extension grate channels, said means providing for movement of said extension 90 grate relative to the dead plate while maintaining intact the fluid connection. 95

3. A stoker comprising an extension grate and a lower grate underlying said extension grate, said extension grate being formed with a plurality of channels for passage therethrough of a liquid-cooling medium, and means for discharging the liquid from the said channels over the surfaces of said lower grate. 100

4. In a stoker, a grate structure comprising a series of elements forming a wall, said elements having at the rear inclined wall surfaces the lower edge of each of which overlies the upper portion of an underlying surface, and means for directing a fluid against one of the said inclined 110 surfaces whereby the said liquid flows by gravity over the surfaces of the underlying elements. 105

5. In a device of the class described, the combination of a lower grate, comprising a series of superimposed elements, each of said elements having a heat absorbing surface and a heat dissipating surface, the latter surface of one element being inclined in a different direction than the corresponding surface of the next adjacent element, and means for directing a cooling medium 115 against said last named surfaces. 120

6. In a device of the class described, the combination of a lower grate, said grate having a heat absorbing portion and a plurality of heat dissipating portions, said last mentioned portions being alternately inclined in different directions and having outer and inner surfaces, and means for directing a cooling medium against said last 125 named portions so that said medium alternately passes along the outer and inner surfaces thereof. 130

JOSEPH S. BENNETT.
